UNITED STATES PATENT OFFICE.

STUART BALLANTINE, OF WHITE HAVEN, PENNSYLVANIA, ASSIGNOR TO RADIO FREQUENCY LABORATORIES, INCORPORATED, OF BOONTON, NEW JERSEY, A CORPORATION OF NEW JERSEY.

METHOD OF AND MEANS FOR REDUCING RETROACTIVE CURRENTS IN PUSH-PULL AMPLIFIERS.

Original application filed April 3, 1923, Serial No. 629,702. Divided and this application filed July 3, 1924. Serial No. 724,123.

To all whom it may concern:

Be it known that I, STUART BALLANTINE, a citizen of the United States, residing at White Haven, in the county of Luzerne and State of Pennsylvania, have invented certain new and useful Improvements in Methods of and Means for Reducing Retroactive Currents in Push-Pull Amplifiers, of which the following is a specification.

10 This invention relates to electrical amplifier circuits of the so-called "push-pull" type such as described in the patent to Colpitts, No. 1,128,292, and an object of the invention is to eliminate or reduce the retroactive or feed-back current due to the grid-plate impedance of the audion amplifying tubes.

15

This application is a division of my co-pending application, Ser. No. 629,702, filed April 3, 1923, which relates to the reduction or elimination of retroactive currents in three-electrode ionic amplifiers, which currents arise from the capacity coupling between the input and output circuits of the 20 amplifier.

In my co-pending application I have described the method of and circuits for balancing the impedance network of a one tube amplifying stage to reduce or eliminate retroactive currents through the grid-plate impedance. In the present case, the output circuit of one ionic amplifying tube is so balanced, according to the methods described in my earlier application, against 25 the output circuit of a similar tube that there is no retroaction from either output circuit upon a common input circuit.

In the accompanying drawings which illustrate embodiments of my invention, 30 Fig. 1 is a symbolic representation of a push-pull amplifying unit comprising two ionic amplifiers;

Fig. 2 is a diagrammatic representation of various forms of impedances which may 35 be employed as the input impedance network for the unit shown in Fig. 1; and

Fig. 3 is a diagram of a balanced push-pull amplifying circuit.

In Figure 1, T_1 and T_2 are ionic amplifiers 40 having a common filament battery A and a common plate battery B. C_{m1} and C_{m2} are intra-electrode capacities of T_1 and T_2 re-

spectively, which produce undesirable reactive effects when unbalanced; Z_{c1} and Z_{c2} are neutralizing impedances which 55 eliminate this retroactive effect. Z_1 and Z_0 are respectively the input and output coupling networks which satisfy the following requirements:

(1) In Z_1 the potential difference between 3 and 4 due to an input voltage impressed between 1 and 2 must be opposite in phase with respect to the common point 4 to the voltage acting between 4 and 5.

(2) In Z_0 the potential difference between 6 and 7 resulting from a flow of A. C. plate currents must be opposite in phase, with reference to point 7, to the voltage acting between 7 and 8.

(3) In Z_0 the impedances between 6 and 7 and between 7 and 8 must include a D. C. path for the direct components of plate current of tubes T_1 and T_2 , since these impedances are in series connection with the plate circuits.

Various forms of connecting network suitable for use at Z_1 and Z_0 are shown in Fig. 2. Separation of the input and output circuit occurs when there is no component of voltage between 3 and 4 and between 4 and 5 due to retroactive currents flowing back through C_{m1} and C_{m2} .

To show how this balance may be obtained in a particular circuit, the embodiment of my invention shown diagrammatically in Fig. 3 is presented. Here the input network corresponding to Z_1 takes the form of a transformer having a primary winding or windings 1-2, and two secondary windings 3-4 and 4-5, while Z_0 is a similar transformer having two primary windings L_1 and L_3 , providing the impedances corresponding to 6-7 and 7-8, respectively, of Fig. 1, and secondary windings L_2 and L_4 , corresponding to the impedance 9-10 of Fig. 1. For the purpose of making the transformer windings resonant to different frequencies, tuning condensers C_3 , C_4 and C_6 may be shunted across the impedances 6-8, 9-10 and 3-5, respectively, or if desired, variable transformers may be used in addition or in lieu of the tuning condensers. The neutralizing impedances in this arrangement take the form of condensers C_1 100

and C_2 which are located, respectively, between points 5 and 6 and between points 3 and 8 of the impedance networks. If the tuning to various frequencies is done by means of the variable condensers, C_3 , C_4 , C_5 , the neutralizing condensers C_1 , C_2 need no readjustment for changing frequencies. If the tuning is done by means of variable transformers, or variable inductances in conjunction with or in lieu of condensers, the combinations L_1 , L_3 and L_2 , L_4 should be varied together for independence of frequency. I have found that this can readily be accomplished by using variotransformers, such as described in my copending applications Serial No. 590,514, filed September 25, 1922, and Serial No. 607,852, filed December 19, 1922, and in the copending application of L. M. Hull, Serial No. 611,118, filed January 6, 1923, when these variotransformers are mechanically connected so that they may be rotated together.

It can be shown by analysis of the circuits that the opposition in phase of the input voltages upon the tubes produces such a phase relation between the output currents that the potentials of G_1 and G_2 are unaffected by currents through C_{m1} and C_{m2} . The load introduced through the windings of Z_0 is so balanced with respect to C_1 and C_2 that the current flowing through L_1 and C_{m1} to G_1 is just neutralized by the current flowing through L_3 and C_2 to G_1 , with a similar relation holding for the currents to G_2 through C_1 and L_1 , C_{m2} and L_3 . This balance can be attained with a variety of different circuit constants, as will be apparent to one skilled in the art. For example, if the ionic tubes T_1 and T_2 have exactly similar characteristics and the load is equally balanced upon the two tubes by making $L_1=L_3$, and $L_2=L_4$, then C_1 must be made equal to C_2 and both bear a ratio to C_{m1} and C_{m2} which depends upon the absolute values of L_1 and L_3 and the constants of the tubes and which can be readily found by experiment in any given case.

While I have described the perfect balancing of the impedance network to secure a complete elimination of the retroactive effect, it will be understood that my invention

is not restricted to a perfect balance, since any tendency towards balance with reduction of the retroaction, or control of it, falls within the scope of my invention. It will also be understood that the invention is not limited to the specific circuit which I have described, since various changes or modifications may be made in the circuits without departing from the spirit of my invention.

I claim:

1. The method of preventing the output circuits of a push-pull amplifying stage from affecting the input circuit of said stage, which comprises balancing the retroactive current due to the output circuit of one tube of said stage by a neutralizing current established by the output circuit of the other tube of said stage.

2. The method of preventing the output circuit of an audion push-pull amplifier network from affecting the input circuit terminals which comprises neutralizing the effect of a retroactive current through the grid-plate impedance of one audion by impressing a second retroactive voltage upon the grid of that audion, said second retroactive voltage being established by the load in the plate circuit of the second audion.

3. An amplifying stage comprising input and output circuits, two audions oppositely connected in said circuits whereby one of said audions is adapted to repeat certain parts, and the other, the remaining parts of incoming waves, and a coupling between said input and output circuits for each of said audions and effective to counteract the effect of retroactive currents through the grid-plate impedance of its respective audion.

4. An amplifying stage comprising input and output circuits, two audions oppositely connected in said circuits whereby one of said audions is adapted to repeat certain parts, and the other, the remaining parts of incoming waves, and a capacity coupling between the grid of each audion and the plate of the other audion.

In testimony whereof, I affix my signature.

STUART BALLANTINE.
